UNITED STATES PATENT OFFICE.

JOHN ECKERT, OF MILWAUKEE, WISCONSIN.

RING-ROLLING MACHINE.

1,367,540.

Specification of Letters Patent.

Patented Feb. 8, 1921.

Application filed February 8, 1919. Serial No. 274,730.

To all whom it may concern:

Be it known that I, JOHN ECKERT, a citizen of the United States, and resident of Milwaukee, in the county of Milwaukee and State of Wisconsin, have invented new and useful Improvements in Ring-Rolling Machines, of which the following is a description, reference being had to the accompanying drawings, which are a part of this specification.

This invention relates to a machine for use in forming unbroken rings from a solid piece of metal and consists in the novel construction and arrangement of the parts as hereinafter described and more particularly set forth in the claims hereof.

The invention further consists in the several features hereinafter set forth.

In the drawings:

20 Figure 1 is a front end view of the ring rolling machine embodying the invention; Fig. 2 is a plan view thereof; Fig. 3 is an elevation view thereof; Fig. 4 is a detail sectional view taken on 25 the line 4—4 of Fig. 2; Fig. 5 is a detail sectional view taken on the line 5—5 of Fig. 1; Fig. 6 is a view of a block of metal; Fig. 7 is a view of a rough blank; Fig. 8 is a view of a roughly formed ring; and, Fig. 9 is a detail view of a modified form 30 of roll.

Referring to the drawings, a piece of 35 metal 9, shown in Fig. 6, is heated and forged into the rough blank 10, shown in Fig. 7, and where the work is large this is done on a steam hammer. The blank 10 is then placed upon a suitable mandrel or die 40 and forged into a rough ring 11 and where the work is large this is done on a steam hammer, after which the heated rough ring is formed to approximate size in the ring rolling machine.

45 The ring rolling machine has a frame consisting of a base plate 12, uprights 13, a rear frame member 14, and spaced apart front frame members 15 and 16.

The rear frame member 14 is provided 50 with spaced shaft bearings 17 and 18, the bearing 18 being pivotally mounted in the arms 19 of the frame 14 by means of trunnions 20 secured to said bearing and journaled in the arms.

55 A fixed bearing 21 is mounted on the front upright 13 between the members 15 and 16

and a movable bearing 22 is vertically slidably mounted between the sides 23 and 24 of the members 15 and 16.

A shaft 25 is journaled in the bearings 17 and 21 and a shaft 26 is journaled in the bearings 18 and 22. A gear 27 on the shaft 25 meshes with a gear 28 on the shaft 26 so that rotation of one of the shafts drives the other in an opposite direction. The shaft 25 is driven by a motor 29 through a worm 30, on the motor shaft 31, meshing with a worm wheel 32 on the shaft 25.

A ring forming die roll 33 is detachably secured to the shaft 25 to be turned thereby 70 and a similar die or roll 34 is detachably secured to the shaft 26 and turned thereby. Each of these dies is provided with an annular groove 35 preferably having sides extending at right angles to the bottom of the 75 groove. The turning of the shafts 25 and 26 rotates the rolls 33 and 34 in opposite directions. The shape of the grooves of the rolls determines the shape of the cross section of the ring and in Fig. 9 I show a roll 80 34' similar to roll 34 and a roll 33' having a groove 35' therein provided with an annular shouldered portion 64 so that an annular flange will be formed on the inner periphery of the ring, a thing which is very 85 difficult and almost impossible to do on a steam hammer.

In order to introduce the rough ring between the dies and to gradually work it into shape, means are provided for elevating and 90 depressing the roll 34 by raising and lowering the front end of the shaft 26 upon which this roll is mounted, said shaft swinging in the trunnions 20 and the teeth of the gears 27 and 28 being long enough to accommodate 95 this swinging movement. This means consists of a shaft 36 carrying an eccentric 37, an eccentric rod 38 pivotally connected by a pin 39 to the bearing 22, and means for rotating the shaft 36. The means for rotating the shaft 36 consists of a worm wheel 40 on said shaft meshing with a worm 41 on a shaft 42 which carries a sprocket 43 connected by a chain 44 to a sprocket 45 on the shaft 26.

Mechanism is also provided to stop the rotation of the shaft 36 after it has made one revolution, consisting of a clutch for drivingly connecting the worm wheel 40 with the shaft 36 and means for automatically throwing out the clutch.

The worm wheel 40 is loosely mounted on

the shaft 36 and is provided with a clutch face 46 which co-acts with a clutch member 47 slidably keyed to the shaft 36 and provided with a clutch face 48. The faces 46 and 48 are normally held in clutching engagement by means of a spring 49 interposed between the member 47 and a collar 50 on the shaft 26. Thus the wheel 40 is normally secured in driving engagement with the shaft 36 and to automatically throw out the clutch a pin 51 is vertically slidably mounted in a bracket 52 and engages a cam projection 53 on the member 47 whereby the wedging of the pin 51 against the projection slides the member 47 on the shaft 36 out of engagement with the wheel 40. The pin 51 is moved out of engagement with the cam by manually actuated means consisting of a lever 54 passing through a slot 55 in the pin, pivotally connected intermediate its ends to the bracket 52, and operatively connected by a link 56 to one end of a bell crank lever 57 mounted on a shaft 58, the other end of said bell crank lever being connected by a link 59 to a foot pedal 60. A weight 61 adjustably mounted on the pin carrying end of the lever 54 normally acts to keep said pin in contact with the member 47.

With this construction, when the pin is holding the clutch out the rolls are separated from each other and a heated roughly formed ring 63 is placed over the lower roll 33 so that a portion of the ring is in line with or is seated in the groove in that ring. Then the operator moves the pin 51 upwardly, releasing the clutch, and the roll 34 is fed downwardly by the eccentric drive previously described, and the rolls are thus brought into rolling contact with the ring, and as the roll 34 moves downwardly pressure is being continuously applied to the inner and outer peripheries of the ring as said ring is revolved between the rolls, so that when the roll 34 starts on its upward movement due to the raising of the eccentric rod 38 by the eccentric 34, the ring has been rolled to approximate size. Just before the roll 34 reaches its upper position, the pin 51 contacts with the inclined side of the cam 53 and thereby throws the clutch out when the roll 34 has reached its upper position. The treated ring is then removed and the operation is ready to be repeated.

After the ring has been rolled to approximate shape on the machine, it may be placed on a mandrel and gaged to the desired size.

To cool the rolls and also remove scale from the ring during the rolling operation, a jet of water is directed upon the upper roll from a pipe 62 connected to any suitable water supply.

To prevent any tendency of the lower end of the ring to swing, it is held between two guide rollers 64 and 65, one of said rollers 65 being mounted on a lever 66 provided with a

foot pedal arm 67 under the control of the operator. The lever 66 is normally moved inwardly to bring the roller 65 into engagement with the ring by a spring 68 yieldingly connecting said member to the frame of the machine so that the ring may be held between the rollers 64 and 65 during the rolling operation and released by pressure upon the foot pedal 67.

What I claim is:

1. In a ring rolling machine, the combination of a pair of spaced apart shafts, means for rotating said shafts in opposite directions, a ring-forming roll mounted on each of said shafts, means for raising and lowering the roll-carrying end of one of said shafts including a rotating shaft, means for automatically stopping the rotation of said last named shaft after a single revolution, and operator-controlled means for rendering said stopping means operative.

2. In a ring rolling machine, the combination of a pair of spaced-apart shafts, means for rotating said shafts in opposite directions, a ring-forming roll on each of said shafts, and means for raising and lowering the roll-carrying end of one of said shafts comprising a bearing at this end of the shaft, a pin on said bearing, a driven shaft, an eccentric on said driven shaft, a member connecting said eccentric with said pin, and means for controlling the operation of said driven shaft.

3. In a ring rolling machine, the combination of a frame having spaced standards, fixed bearings mounted in said standards, a shaft journaled in said bearings, another bearing carrying trunnions pivotally mounted in one of said standards, and a bearing slidably mounted in the other standard, a shaft journaled in said pivoted and sliding bearings, said shafts carrying co-operative ring-forming rolls, a gearing connection between said shafts, means for driving the first named shaft, a third shaft for vertically moving the second-named shaft, a driving connection between said said first named shaft and third shaft, and a driving connection between said third shaft and sliding bearing.

4. In a ring rolling machine, the combination of a pair of spaced-apart shafts, means for rotating said shafts in opposite directions, a ring-forming roll mounted on each of said shafts, means for raising and lowering the roll-carrying end of one of said shafts including a driven shaft, a constantly rotating shaft, a gearing connection between said driven shaft and rotating shaft, clutch mechanism for said gearing connection, and means for automatically throwing out said clutch mechanism to stop the rotation of the driven shaft, and operator-controlled means for rendering said clutch throw-out means operative.

5. In a ring rolling machine, the combination of a pair of spaced apart shafts, means for rotating said shafts in opposite directions, a ring-forming roll mounted on each of said shafts, means for raising and lowering the roll-carrying end of one of said shafts including a rotating shaft, and means for automatically stopping the rotation of said last named shaft after a predetermined 10 movement.

6. In a ring rolling machine, the combination of a pair of spaced apart shafts, means for rotating said shafts in opposite directions, a ring-forming roll mounted on each of said shafts, and means for lower- 15

ing the roll-carrying end of one of said shafts including a driven shaft operatively connected thereto, a worm wheel mounted on said driven shaft, a clutch connection between said worm wheel and said driven shaft, and a worm meshing with said worm wheel and driven by the other roll-carrying shaft. 20

In testimony whereof, I affix my signature, in presence of two witnesses.

JOHN ECKERT.
